UNITED STATES PATENT OFFICE.

JOSEPH M. PICKERING, OF PHILADELPHIA, PENNSYLVANIA.

BRUSH-MAKING MACHINE.

SPECIFICATION forming part of Letters Patent No. 317,570, dated May 12, 1885.

Application filed October 13, 1883. (No model.)

To all whom it may concern:

Be it known that I, JOSEPH M. PICKERING, a citizen of the United States, residing at Philadelphia, in the county of Philadelphia and 5 State of Pennsylvania, have invented a new and useful Improvement in Needles for Use in Brush-Making, of which the following is a specification.

One feature of my invention relates to novel 10 means whereby the wire is clamped to the needle - handle for enabling proper tensile strain to be applied to the wire which is used for confining the tufts of bristles in a brush block or stock; and said means consist of a 15 two - part handle provided with clamping- plates, which afford a reliable grip upon the wire when closed thereon under pressure by the hand of the operator.

Another feature of my invention has for its 20 object an always accessible space for the reception of a tuft of bristles near the outer end of the needle after it has been passed through a tuft-hole in a brush-block. Heretofore such needles have been practically straight, and 25 therefore more or less manipulation was requisite for placing the tufts of bristles in such position between the needle and the wire as would afford the loop needed to enable the tuft to be thereafter drawn into its seat in the 30 brush-block; but my improved needle is bent at its outer end at an angle or curve from its straight shank and in the plane occupied by the eye, so that a wire passing rearwardly from the eye in a straight line is so far re- 35 moved from the adjacent side of the needle as to always afford a tuft-receiving space. As essential features in construction my bent needle is channeled or longitudinally grooved from the eye rearwardly at the back of the 40 bent end for partially housing the wire, and the needle-eye is rounded at its rear end and inclined at its outer end, and a brush-maker's needle with such an eye is novel, whether with or without the bent feature.

I am aware that sewing-machine needles 45 have been bent so as to be operated in the arc of a circle, and also that all needles have eyes so rounded and finished as to avoid cutting thread; but I know of no prior needle having 50 the inclined outer end at its eye and otherwise so constructed as to be of practical service as a brush-maker's needle, which, being

used with wire, must enable considerable tensile strain to be applied thereto without making a bend or bight in the wire, and this is 55 obviated by providing the eye with an inclined outer end.

In the accompanying drawings, which make 60 a part of this specification, Figure 1 is a side view of the needle A and handle B. Fig. 2 is 65 a top view of the needle and handle, the jaw 2 being thrown upward and backward. Fig. 3 is a vertical section at the broken line $x-x$ of Fig. 1. Fig. 4 is a longitudinal section of the needle A.

Like letters of reference in all the figures indicate the same parts.

A represents a needle for wiring the tufts of bristles into the stock, the wire being looped over the tufts in the usual manner, grasping 70 them, respectively, as the needle is drawn through the holes of the stock. It is provided with a handle, B, composed of two parts, 1 and 2, hinged together by means of the joint-pin a . The outer end of the needle is inserted 75 in the hole b of the part 1 of the handle, and confined by means of the set-screw c .

C are steel plates the faces of which are arranged to form teeth in the manner of files, whereby to hold securely the drawing-wire D, 80 which is passed through holes in the part 1 of the handle. They are dovetailed into the inner faces of the handle, as shown in Figs. 1 and 2, to hold them securely in place, and they grasp the wire tightly during the draw- 85 ing in of the tufts.

The eye end of the needle is bent in the manner shown in the drawings.

As hereinbefore stated, brush-makers' needles have heretofore been straight, as shown, 90 for instance, in the United States Letters Patent of Joseph Pickering, October 24, 1871, No. 120,164, and therefore with such needles the wire must be manipulated for properly looping a tuft of bristles, while, as seen in Fig. 95 4, the bent needle affords a readily-accessible space between the wire D and the bent portion of the needle for the ready reception of a tuft of bristles. It will also be seen that the bend or curve of the needle is in the vertical 100 plane occupied by the eye, so that the wire can pass directly downward through the eye, and thence rearwardly beneath the bent or curved portion of the needle.

Said needle has a longitudinal groove, *e*, cut in its upper side to receive the wire *D*, the eye *f* being carried forward from the groove on an angle, as shown in Figs. 1 and 4, terminating 5 near the end of the needle at the opposite side from the groove. If the inner end of the eye had a sharp corner or corners, as the needle is pushed forward the wire in pressing thereon would be weakened, and to prevent this I 10 round the end of the eye completely from side to side of the needle, as shown in Figs. 1 and 4, and thus prevent any injury to the wire. The outer end of the eye being inclined, as clearly shown in Fig. 4, enables a strong pull 15 to be given to the wire without causing a bend therein, it being obvious that the wire will occupy a practically straight line in passing outwardly and forwardly from the groove or channel *e* through the eye.

20 I claim as my invention—

1. The brush-maker's needle having a handle in two parts hinged together, and provided with grasping or clamping plates, substan-

tially as described, whereby wire is securely held during the operation of wiring tufts of 25 bristles into brush-blocks, as set forth.

2. The brush-maker's needle having an eye near its point, and its outer end bent or curved in the plane occupied by the eye, and a longitudinal groove on its upper side opposite 30 said bend, substantially as described, whereby a loop-receiving space is afforded below the bent portion of the needle when the wire extends rearwardly from the eye, as set forth.

3. In a brush-maker's needle, an eye near 35 the point thereof, having a rounded inner end and an inclined outer end, substantially as described, whereby tensile strain can be applied to a wire passing along said needle and forwardly through said eye without materially 40 bending said wire, as set forth.

JOSEPH M. PICKERING.
